C. E. LOMBARD,
FASTENING DEVICE,
APPLICATION FILED NOV. 11, 1915.

1,203,885.

Patented Nov. 7, 1916.

UNITED STATES PATENT OFFICE.

CHARLES E. LOMBARD, OF EAST WILTON, MAINE.

FASTENING DEVICE.

1,203,885.

Specification of Letters Patent.

Patented Nov. 7, 1916.

Application filed November 11, 1915. Serial No. 60,930.

To all whom it may concern:

Be it known that I, CHARLES E. LOMBARD, a citizen of the United States, residing at East Wilton, in the county of Franklin and State of Maine, have invented a new and useful Fastening Device, of which the following is a specification.

This invention relates to a fastener for covers such as used, for example, upon milk cans and the like, one of the objects of the invention being to provide a simple and efficient fastener which can be readily shifted to position to connect the cover to the can and which can be quickly adjusted to bind 15 the cover securely on the can, thus to effectually seal it.

A further object is to provide a fastening utilizing nuts for tightening the same, the nuts being so mounted that, when turned 20 in one direction for the purpose of tightening the fastening, they will direct the fastening into engagement with the neck portion of the can so that the fastening will be successively shifted to engaging position 25 and then tightened during one operation of screwing the nuts.

With the foregoing and other objects in view which will appear as the description proceeds, the invention resides in the combination and arrangement of parts and in the details of construction hereinafter described and claimed, it being understood that changes in the precise embodiment of the invention herein disclosed, can be made 35 within the scope of what is claimed, without departing from the spirit of the invention.

In the accompanying drawings the preferred form of the invention has been shown. 40 In said drawings:—Figure 1 is a side elevation of a portion of a can having a cover secured thereon by means of a fastening such as constitutes the present invention. Fig. 2 is a plan view of the structure shown in Fig. 1. Fig. 3 is a section on line A—B Fig. 2. Fig. 4 is a detail view of one end portion of the fastening bolt.

Referring to the figures by characters of reference 1 designates the neck portion of a can the mouth of which is surrounded by a band 2 which can be secured thereto in any desired manner and which forms an annular shoulder 3 at the lower edge thereof. If preferred, this band can be made integral 55 with the can.

The cover 4 is adapted to be inserted into

the mouth of the can and has a continuous groove 5 in the lower face thereof for the reception of the upper edge portion of the can. Outstanding from the peripheral portion of the cover are ears 6 each of which has a bore 7 extending therethrough. In each bore a bolt 8 is mounted for rotation there being a segmental head 9 at the lower end of the bolt while the upper end thereof is screwthreaded, as at 10 and is engaged by a wing nut 11. This wing nut has an annular groove 12 in the lower end portion thereof and in this groove is seated an eye 13 formed at the upper end of a spring finger 14 which is soldered or otherwise fastened to the ear 6. Extending downwardly from the outer end portion of the ear is a stop finger 15 designed to limit the rotation of the head 9.

In applying a cover and securing it by means of the fastening constituting the present invention, said cover is placed in position while the heads 9 are in contact with the stop fingers 15. After the cover has 50 been properly positioned, the nuts 11 are successively tightened. As each nut 11 is turned to the right for the purpose of tightening it, its frictional engagement with the threaded bolt 10 will cause said bolt to turn 55 therewith and to move its head 9 into position under the shoulder 3, the convex face of the head coming against the side of the can. Continued rotation of the nut will result in forcing the head against the shoulder 60 so as to cause the cover to be pulled tightly down onto the mouth of the can, thus sealing the same. After all of the fastening devices have thus been tightened, the cover will be securely held in position. By 65 turning each nut in the opposite direction, it will be held to the ear 6 by the spring 14 so that rotation of the nut will result first in the downward movement of the bolt 8 so as to disengage the head 9 from shoulder 3 70 after which the frictional engagement of the nut with the bolt will result in the head being swung outwardly against the stop finger 15.

From the foregoing it will be apparent 75 that but one operation is necessary either to apply or to disengage the bolt from the can. The first or applying operation is effected by the rotation of the nut in one direction to successively move the head 9 into 80 engagement with the shoulder 3 and to tighten the head thereagainst, while the op-

eration of releasing the cover merely results in the continuous rotation of the nut in one direction to successively shift it out of engagement with the shoulder 3 and to then 5 swing it back against the finger 15.

Importance is attached to the fact that the cover can be placed in any position desired on the can and the heads 9 will always move properly into engagement with the 10 shoulder 3 when shifted in the manner pointed out. It is not necessary to provide any special recesses for the reception of the heads 9.

What is claimed is:—

15 The combination with a can having an annular shoulder, of a cover detachably mounted on the can, outstanding ears thereon, bolts mounted for rotation in the respective ears, each bolt having a segmental head at its 20 lower end, a nut threaded upon the upper

end of each bolt, means for holding each nut against the top of the ear, each nut constituting means for successively swinging the head of its bolt into engagement with the shoulder and for tightening said head 25 against the shoulder, thereby to bind the cover upon the can, and a stop depending from each ear for limiting the rotation of the adjacent head away from the shoulder, said head being movable into engagement 30 with the shoulder at any desired point therealong.

In testimony that I claim the foregoing as my own, I have hereto affixed my signature in the presence of two witnesses.

CHARLES E. LOMBARD.

Witnesses:

E. A. RUSSELL,
NORMAN YEATON.
